ELECTRIC POWER MECHANISM FOR
OPERATING AWNINGS

John Lenard Stuart, Oakland, Calif.

Application December 2, 1931. Serial No. 578,517

3 Claims. (Cl. 156—44)

The present invention relates to electric power operated means especially adapted for, although not confined to, the purpose of extending and retracting awnings.

5 The principal object of the invention is to provide an electric power mechanism for awnings of such size and construction that it can be mounted in a concealed or partly concealed position adjacent to the roller upon which the awning is 10 wound, and which does not project from or mar the appearance of the building wall, either upon its inner or outer face. When the awning roller is mounted in a recess of standard size formed in the face of the wall, my power mechanism can 15 be wholly housed within the recess, and when the awning roller is mounted upon the face of the wall or beneath a protecting hood upon the transom-bar, my mechanism can be installed upon the face of said wall or transom-bar immediately 20 beneath the roller. In either position the mechanism is at least partly concealed, and is inconspicuous, and requires no additional bracket or housing projecting from the wall, or supplementary recess within the wall.

25 Another object of the invention is to provide an electric power mechanism in which a motor and speed reducing gearing are inclosed within a single casing of elongated cylindrical form and small diameter, either with or without an automatic controlling switch, and in which a very great reduction of speed is obtained. Still further objects and advantages of the invention will 30 become apparent from the following specification, which should be read with the understanding that changes within the scope of the appended claims, may be made in the form, construction and arrangement of the several parts described in said specification and shown in the accompanying drawings, without departing from the 35 spirit of the invention as set forth in said claims. It is also to be understood that the invention is not limited to a device for operating awnings, but may be embodied in power mechanisms for other purposes.

45 My invention will now be described with reference to the accompanying drawings which illustrate one embodiment thereof and in which

Fig. 1 is a plan view, partly in section, of a portion of a building wall with a recess therein, in which is mounted an awning and my electric power mechanism for operating the same.

50 Fig. 2 is a longitudinal front view on a larger scale, and partly in section, of my electric power mechanism.

Fig. 3 is a sectional plan view of the automatic control switch taken on the line 3—3 of Fig. 2.

Fig. 4 is a vertical section taken on the line 4—4 of Fig. 1 and enlarged, showing the arrangement of my power mechanism and the awning in a recess, the awning being shown fully retracted.

Fig. 5, 6 and 7 are transverse sections taken on the respective correspondingly numbered lines of Fig. 2.

Fig. 8 is a section similar to Fig. 4, but on a smaller scale, showing an arrangement of mounting my power device and an awning upon a common type of transom-bar used in store front construction.

Fig. 9 is a diagram illustrating conventionally a preferred arrangement of electric circuits for operating and controlling my power device.

In the drawings, the reference numeral 11 designates a building wall which is provided 75 with a horizontal recess 12, as shown in Figs. 1 and 4, or which has a transom-bar 13 provided with a projecting hood 14, as shown in Fig. 8. In the latter construction, the transom-bar forms a solid strip across the front of the building and 80 is usually positioned between the ground floor show windows and the mezzanine windows, neither of which are shown.

The awning fabric or cover is designated by the numeral 18, and it is wound upon a roller 19 85 suitably mounted in any usual manner, not shown, within the recess 12 or in front of the transom-bar 13. The outer edge of the awning is provided as usual with a pole or bar 20 from which hangs a valance 21. When the awning 90 is fully retracted, the valance 21 covers and closes the open front of the recess 12, as shown in Fig. 4, or forms a protecting and inclosing cover in front of the transom-bar 13, as in Fig. 8. The means for supporting the outer edge or bar 20 of 95 the awning have been omitted as forming no part of the present invention, it being understood that any customary arrangement of awning frame may be used, which will permit the awning to be extended and retracted by or upon 100 rotation of its roller 19.

My electric power mechanism, designated generally by the numeral 22, is inclosed within an elongated preferably cylindrical shell of a diameter small enough to enable it to be mounted entirely within the recess 12 or beneath the protecting hood 14 of the transom-bar. The dimensions of such recesses and transom-bars are fairly well standardized in building construction to provide a free space of approximately 8 inches 110

deep by $8\frac{1}{2}$ inches high for the mounting of the awning. In actual practice, the diameter of my power device 22 is approximately $5\frac{1}{4}$ inches, allowing it to be entirely housed, with the awning roller, within the recess or in front of the transom-bar and beneath the hood thereof, without projecting over and obscuring any portion of the show window. My power device is positioned at any desired point in the width of the awning, parallel to and beneath and in front of the roller 19. A rotating sprocket 23, Fig. 4, extends from one end of the power device and is connected with a similar sprocket 24 on the awning roller shaft by a suitable chain indicated at 25. Thus 15 my power device is inconspicuous, and requires no projecting bracket or housing to mar the face of the building. In the recess construction, as shown in Fig. 4, when the awning is fully retracted, the entire mechanism is concealed, and in the transom-bar construction illustrated in 20 Fig. 8, it is only slightly less concealed. Brackets 26 secure the power device 22 to the rear wall of the recess or to the transom-bar.

My power mechanism comprises an electric 25 motor 27 at one end, a speed reducing gear mechanism 28 in the center and an automatic controlling switch mechanism 29 at the other end, as shown in Fig. 2. The motor, in order to provide sufficient power within so small a diameter, 30 must necessarily operate at high speed, in practice about 3500 R. P. M. The driven shaft, upon which is carried the sprocket 23, must turn at only a few revolutions per minute, so that a great reduction in speed must be obtained in the gear 35 mechanism. In order to accomplish this reduction in speed, I employ a two stage worm mechanism arranged in such a manner as to enable it to be housed within a space of the same diameter as that of the motor. The motor shaft 40 is connected by a separable coupling 31 with a short longitudinal shaft 32 upon which is secured a worm 33. The latter meshes with a worm wheel 34 upon a transverse shaft 35, which also carries a spur gear 36, Figs. 2 and 5. The gear 45 36 meshes with a spur gear 37, Figs. 2 and 6, secured upon a transverse shaft 38 parallel to the shaft 35. The shaft 38 also carries a worm 39 which meshes with a worm wheel 40 upon the driven or low speed shaft 41. Bearings are provided at 42, 42' and 42'' for the driven shaft, and at 43 and 43' for the driving or high speed shaft, one of the latter, 43', being a step bearing within the end of the driven shaft. The entire gear mechanism is housed within an extension 44 of the shell of the motor, and suitable grease retainers are provided at 45 to enable the gear housing 44 to be filled with lubricant.

The automatic control switch is housed within 60 a separate shell 46, secured to the end of the shell 44 and having the same diameter. For purposes of construction, the inner end of the switch housing 46 carries the center bearing 42' of the low speed shaft, and its inner end bearing 42 is carried by a plate 47 secured between the switch housing 46 and the gear housing 44. The outer end bearing of the driven shaft is carried by a separate plate 48 forming the end of the switch housing 46.

The function of the switch mechanism is to 70 stop the motor when the awning reaches either end of its travel. To accomplish this, two contacts are provided, opening respectively at the inner and outer limits of awning movement, and operating with a manually controlled starting

switch, in a manner to be described hereinafter, to control the operation of the motor.

The slow speed shaft 41 is provided with a worm 49, Figs. 2, 3 and 7, which meshes with a worm wheel 50 secured to a sleeve 51 journaled upon a vertical spindle 52. The upper end of said sleeve is provided with a cam 53 adapted to bear against a follower 54 upon a contact arm 55. The arm 55 is pivoted at 56 to a suitable mounting 56' secured upon an insulating plate 57 mounted within the switch housing. The free end of the arm 55 is adapted for contact with an adjustable screw 58 carried by a bracket 59 also secured to the insulating plate 57. A spring 60 normally holds the arm 55 in contact with the screw 58, and said contact is broken by the cam 53 as shown in Fig. 3. The worm wheel 50 has a downwardly extending hub 61, Fig. 7, upon which is slidably mounted a sleeve 62 carrying a cam 62'. The latter is yieldably held against the worm wheel 50 by a spring 63 acting against a plate 64 secured to the lower end of the spindle 52. The cam 62' operates a second contact arm 65, Fig. 2, identical with but electrically separate from the previously described arm 55. The arm 65 makes or breaks contact with an adjustable screw 66 mounted similarly to but electrically separate from the screw 58.

Adjustment is provided between the lower cam 62' and the worm wheel 50 by means of a flange 67 formed integral with said cam and provided with a series of holes 68 adapted for engagement with pins 69 extending downwardly from said worm wheel. The pins are preferably formed upon the ends of screws 70 which hold the sleeve 51 of the upper cam to the worm wheel. By sliding the lower cam downwardly against the action of the spring 63, the pins 69 are freed from the holes 68, and said cam can be rotated with respect to the worm wheel and the upper cam.

An emergency cut out device is preferably provided to insure the stopping of the motor when the awning reaches its retracted position. This is desirable because, if the cam mechanism above described is so set as to stop the motor at the proper time when the awning is dry, it will not function properly when the awning is wet and therefore shrunk to slightly less length. The emergency cut out comprises a spring arm 71, Fig. 7, fastened at 72 to the cover plate 73 of the switch housing, and extending upwardly in front of said housing. An extension 74 is secured to the end of the arm 71 and is positioned for engagement by the awning front bar 20 when the awning is fully retracted. The connection 74' between the extension 74 and the spring arm 71 is adjustable to enable said extension to be moved up or down to insure its engagement by the bar 20. A rod 75 of insulating material is secured to the spring arm 71 and extends through the cover plate 73 to a position immediately in front of the upper contact arm 55. Therefore, when the awning bar 20 engages the extension 74, it moves the arm 71 rearwardly, causing the rod 75 to push the contact arm 55 away from its contact with the screw 58, thereby breaking the circuit.

The electrical connections for operating my power mechanism may be arranged in any suitable manner, as for example, as shown conventionally in Fig. 9, in which L are the line wires supplying current, and R is a suitable reversing switch or relay for controlling the motor 150 27. The control circuits may be connected either

directly with the line or through a transformer T. S is a manual switch by which the motor may be started in either direction or stopped. This switch connects the control current with either 5 of the contact screws 58 or 66 of the automatic switch, and the contact arms 55 and 65 of said automatic switch are connected with the motor control relay R. Therefore when the manual switch S is turned to the position opposite from 10 that in which it is shown, a control current will flow through the automatic contacts 66 and 65, and will operate the relay R to start the motor in a direction to extend the awning. When the cam operates the arm 65 to break the contact, 15 the relay R shuts off the motor current. Then when the manual switch S is turned to the other side, as shown, the control current flows through the contacts 58 and 55, which are now closed, to the relay R, causing the motor to start in the 20 opposite direction to retract the awning. This operation continues until the cam operates the arm 55 to break the circuit, whereupon the motor stops. For simplicity in illustration, the two cams 25 53 and 62' are shown as one in Fig. 9.

The automatic switch is timed to stop the motor at the proper points in the travel of the awning in the following manner. The worm 49 and worm wheel 50 are so proportioned as to cause said worm wheel to make less than one 30 revolution during the total travel of the awning, and said worm wheel is so positioned with respect to the worm that its fixed upper cam 53 will operate the upper arm 55 to break its contact when the awning is fully retracted. The lower cam is then set with respect to the worm wheel and the upper cam so as to cause it to 35 operate the lower contact arm 65 to break its contact when the awning reaches the opposite end of its travel i. e. when it is fully extended. The initial setting of the worm wheel with respect to the worm, to time the upper cam, is accomplished by loosening the stud 52, allowing the worm wheel to be disengaged from the 40 worm. The setting of the lower cam is accomplished by sliding it downwardly against the action of the spring 63 and turning it to the proper position. Closer adjustment of the time of breaking the contact is accomplished by turning the contact screws 58 and 66 in or out.

If for any reason the automatic switch fails 45 to stop the motor when the awning reaches the end of its retracting movement, as for example when the cover 18 is wet and therefore shrunk, the auxiliary or safety device will operate, by contact between the awning front bar 20 and the

spring arm 71, to break the contact between the upper switch arm 55 and its screw 58, thereby stopping the motor when said front bar reaches its fully retracted position, even if the cam 53 has not yet broken said contact.

It will be seen from the foregoing that, by housing a motor, speed reducing gearing, and automatic switch in an elongated cylindrical housing of relatively small diameter, I am able to produce a power mechanism, suitable for operating an awning, which can be mounted conveniently and easily in a partly concealed or inconspicuous position adjacent to the awning roller, so that no bracket, housing, or recess is necessary except that which supports and houses the awning itself. Moreover, by providing a two stage worm gear mechanism, I am able to make a compact power device suitable for operating awnings or for other uses in which low speed is required.

I claim:—

1. In combination with an awning having a retractable flexible cover and a front bar secured to the outer edge thereof, power mechanism for retracting said cover, a movable member positioned for engagement by said front bar when the awning is retracted, and means actuated by said movable member for stopping said power mechanism.

2. In combination with an awning having a retractable flexible cover and a front bar secured to the outer edge thereof, electrically operated power mechanism for retracting said cover, a switch for controlling said power mechanism, and a movable operating arm for said switch, said arm being positioned for engagement by said front bar when the awning is retracted.

3. An awning structure comprising a roller, a flexible cover wound thereupon, an electric motor, speed reducing gear mechanism positioned at the end of said motor and connected therewith, a shaft driven by said motor through said gear mechanism and extending endwise therefrom, a switch positioned at the end of said gear mechanism remote from said motor, said switch being operated by said shaft to stop said motor after a predetermined number of revolutions of said shaft, a substantially cylindrical housing enclosing said motor, gear mechanism and switch in a unit, said housing unit being mounted beside said roller and parallel thereto, said shaft extending from said housing, and power transmitting connections between said shaft and said roller.
